CLAIM

I claim the ornamental design for a roller therapy device, as shown and described.

DESCRIPTION

FIG. 1 is a side perspective view of a roller therapy device having a base component, a ball, and an annular component. FIG. 2 is an exploded perspective view of the roller therapy device.

FIG. 3 is a side elevation view of the roller therapy device. FIG. 4 is a bottom plan view of the roller therapy device. FIG. 5 is a cross-sectional view of the roller therapy device taken along line 5-5 in FIG. 4.

FIG. 6 is a cross-sectional view of the base component of the roller therapy device taken along line 5-5 in FIG. 4, the base component removed for ease of illustration; and, FIG. 7 is a perspective view of the annular component of the roller therapy device, the annular component removed for ease of illustration.

The broken lines shown in the figures are for illustrative purposes only and are not part of the claimed design.
